US00D891544S

(12) **United States Design Patent**
O'Brien et al.

(10) Patent No.: **US D891,544 S**
(45) Date of Patent: ** Jul. 28, 2020

(54) **HAND HOLD FOR CLIMBING DEVICE**

(71) Applicant: **BRAND 44 TRADING LLC**, Denver, CO (US)

(72) Inventors: **Ed O'Brien**, Denver, CO (US); **Amanda Lacy**, Portland, ME (US)

(73) Assignee: **BRAND 44 TRADING LLC**, Denver, CO (US)

(**) Term: **15 Years**

(21) Appl. No.: **29/667,256**

(22) Filed: **Oct. 19, 2018**

(51) LOC (12) Cl. **21-02**

(52) U.S. Cl.

USPC **D21/694**

(57) **CLAIM**

The ornamental design for a hand hold for climbing device, as shown.

DESCRIPTION

FIG. 1 is a top perspective view of the hand hold for climbing device;

FIG. 2 is a bottom perspective view thereof;

FIG. 3 is a top view thereof;

FIG. 4 is a bottom view thereof;

FIG. 5 is a left view thereof;

FIG. 6 is a right view thereof;

FIG. 7 is a front view thereof;

FIG. 8 is a rear view thereof;

FIG. 9 is a cross-sectional view taken along the line 9-9 of FIG. 1; and,

FIG. 10 is a cross-sectional view taken along the line 10-10 of FIG. 3.

The broken lines in the drawings are for the purpose of illustrating portions of the hand hold for climbing device, which form no part of the claimed design.

1 Claim, 10 Drawing Sheets
